UNITED STATES PATENT OFFICE

JOHN H. HICKEY, OF SAN FRANCISCO, CALIFORNIA

REFILLABLE CARTRIDGE FUSE

Application filed August 20, 1928. Serial No. 300,818.

My invention relates to improvements in cartridge fuses wherein the ends of a fusible element are arranged to be detachably clamped between a pair of clamping plates 5 detachably secured upon the ends of a fuse casing, said plates being arranged to obtain an efficient electrical contact and to effectually seal the ends of the casing.

The primary object of my invention is to 10 provide an improved fuse construction.

Another object is to provide an improved cartridge fuse which may be easily and quickly refilled.

A further object is to provide an improved 15 construction which will insure a positive electrical contact with the ends of a fusible element.

Another object is to provide an improved construction which will effectually seal the 20 ends of the fuse casing when assembled.

A still further object is to provide an improved fuse construction which is simple and economical in construction and which can be readily refilled without the use of tools of 25 any kind and without special skill or experience.

I accomplish these and other objects by means of the improved device disclosed in the drawings forming a part of the present application 30 wherein like characters of reference are used to designate similar parts throughout the specification and drawings, and in which—

Fig. 1 is a side elevation, partly in longitudinal section, of my improved fuse;

Fig. 2 is a side elevation, partly in longitudinal section taken at right angles to the position shown in Fig. 1, and with the cap removed and the outer clamping plate swung 40 outwardly to disengage the end of the fusible element;

Fig. 3 is an end elevation of the fuse;

Fig. 4 is a plan view of the fuse as shown in Fig. 2; and

Fig. 5 is an enlarged side elevation, partly in section, of the clamping means.

Referring to the drawings, the numeral 1 is used to designate in general a casing formed from fiber tubing or other suitable material.

50 A fusible element 2, of suitable size and form

is inserted to extend longitudinally through the casing 1. The ends of said fusible element 2 are engaged by clamping means mounted upon each end of the casing 1 and consisting of inner plates 3 arranged to seat upon shoulders 4 formed within opposite ends of the casing, and outer plates 6 eccentrically pivoted upon the inner plates 4 by means of pivot pins 7. The outer plates 6 are made of a diameter slightly larger than the plates 3 and are arranged to seat upon the ends of the casing 1. Openings 8 are formed in the inner plates 3, preferably at one side thereof as disclosed in Fig. 4 of the drawings, to admit the ends of the fusible element 2 therethrough. The pivot pins 7 are preferably arranged to afford a slight axial movement of the plates 3 and 6 relatively to each other to accommodate various thicknesses of fusible elements 2, this axial movement being obtained in the structure illustrated more in detail in Fig. 5 of the drawings by providing a head 9, upon the inner end of each pin 7, arranged to be received within a recess 11 formed upon the inner side of the adjacent inner plate 3. The outer ends of the pins 7 are shouldered as at 12 to seat the outer plates 6 and the extreme outer end is riveted as at 13 to permanently retain the plates together.

Caps 14 are threaded or otherwise detachably mounted upon the ends of the casing 1, said caps being arranged to be advanced to engage and press the clamping plates 3 and 6 against their seats upon the ends of the casing. The caps are preferably spun from tubular material to form inwardly disposed annular flange portions 16 arranged to seat against the outer surfaces of the outer plates 6.

In operation the ends of the fusible element 90 are inserted through the openings 8 in the inner plates 3, the caps 14 being removed and the outer plates 6 swung outwardly upon the pivot pins 7 as shown at the top of Fig. 2. The outwardly extending ends of the fusible elements are then bent over against the outer surface of the adjacent inner plate and the outer plates 6 swung into axial alignment with the inner plate, thereby clamping the bent ends of the fusible elements between the 100

inner and outer plates and covering said bent ends completely. When the outer plates 6 are thus swung to axial alignment the edges of said plates match with the ends of the casing and seat thereagainst. The caps 14 are then applied and advanced to press the outer plates firmly against the ends of the fusible element and at the same time to press the inner plates 3 against the shoulders 4 and the outer plates 6 against the ends of the casing. In this manner the plates 6 are effectually held in electrical contact with the fusible element and with the caps 14. The flange portions 16 seat firmly against the plates 6 and hold said plates seated upon the ends of the casing, thereby effectually sealing the casing and preventing the expansion and escape of gas past said plates 6 when the fusible element is blown in service.

To refill the fuse after the fusible element has been blown, the caps 14 are removed and a new fusible element 2 inserted as above explained. In assembling and in refilling the fuse, no special tools are required, and no particular experience or skill is required as the parts cannot be incorrectly assembled. The outer plates 6 must be turned to proper registering relation to the end of the casing before the caps 14 can be applied, thereby insuring an effective sealing of the casing when assembled. The fusible element is entirely enclosed, and the assembled fuse operates and is used in all respects as an ordinary non-refillable fuse. The slight axial movement between the plates 3 and 6 permits the use of various thicknesses of fusible material for various capacities.

While I have illustrated and described only the preferred construction and arrangement of my improved fuse, the device is of course subject to modification in numerous details without departing from the spirit of my invention. I therefore desire to avail myself of all such modifications as may fall within the scope of the appended claims.

Having thus described my invention what I claim as new and desire to secure by Letters Patent is:—

1. A fuse comprising a casing; a fusible element extending longitudinally through the casing; clamping means mounted upon the ends of the casing and comprising a pair of plates pivotally connected together to receive and clamp the ends of the fusible element, the inner plate of each pair being arranged to seat upon a shoulder formed within the end of the casing and the outer plate being arranged to seat against the end of the casing; and caps detachably engaging the ends of the casing for securing the clamping members in contacting relation to the fusible element and in sealing relation to the casing.
2. A fuse comprising a casing; a fusible element extending longitudinally through the casing; clamping means mounted upon

the ends of the casing and comprising an inner plate arranged to seat upon a shoulder within the end of the casing and an outer plate eccentrically pivoted upon the inner plate and arranged to seat against the end of the casing, the inner plate having an opening arranged to admit the adjacent end of the fusible element therethrough and the outer plate being arranged to be moved pivotally to cover and press the end of the fusible element against the inner plate; and caps detachably engaging the ends of the casing and arranged to hold the clamping means in contacting relation to the fusible element and in sealing relation to the casing.

3. A fuse comprising a casing; a fusible element extending longitudinally through the casing; clamping means mounted upon the ends of the casing and comprising an inner plate arranged to seat upon a shoulder formed within the end of the casing and an outer plate eccentrically pivoted upon the inner plate and arranged to seat against the end of the casing to close the same, the inner plate having an opening formed therein to admit the adjacent end of the fusible element therethrough whereby said end may be bent against the outer surface of the inner plate and the outer plate swung into contacting relation to said end and covering said end and the end of the casing; and caps threaded onto the ends of the casing and arranged to press the outer plate into contacting relation to the end of the fusible element and into sealing relation to the end of the casing.

4. A fuse comprising a casing; a fusible element extending longitudinally through the casing; clamping means mounted upon the ends of the casing and comprising an inner plate arranged to seat upon an annular shoulder formed within the end of the casing and having an opening arranged to admit an end of the fusible element therethrough and an outer plate of slightly larger diameter arranged to seat upon the end of the casing in matching relation thereto; a pivot pin connecting the plates at a point spaced from the centers of the plates, said pin being arranged to permit eccentric relative pivotal movement and a slight axial sliding movement; and caps threaded onto the ends of the casing and arranged to press the outer plate into contacting relation to the end of the fusible element and into sealing relation to the end of the casing.

In witness whereof, I hereunto set my signature.

JOHN H. HICKEY.
